UNITED STATES PATENT OFFICE.

ADOLPH Y. S. ALBUM, OF CHICAGO, ILLINOIS.

BOTTLE STOPPER.

1,419,003.

Specification of Letters Patent. Patented June 6, 1922.

Application filed May 4, 1921. Serial No. 466,748.

To all whom it may concern:

Be it known that I, ADOLPH Y. S. ALBUM, a citizen of the United States, residing at Chicago, in the county of Cook and State of Illinois, have invented a certain new and useful Improvement in Bottle Stoppers, of which the following is a full, clear, concise, and exact description, reference being had to the accompanying drawings, forming a part of this specification.

My invention relates to bottle stoppers, particularly the flat cardboard variety used largely on milk bottles.

One of the objects of the invention is to provide a simple and practical construction of bottle stopper of the class mentioned.

Another object of the invention is to provide a construction which can be manufactured in large numbers at very low expense.

Another object of the invention is to provide a pulling tab from the material which is ordinarily wasted in the production of these caps, so that the manufacture will be highly economical, the tab in the present invention not requiring any additional operations for securing or forming it on the milk bottle cap as is now customary, the tab being formed and produced at the same time the cap is stamped from the stock.

Another object of the invention is to secure extreme simplicity without sacrificing effectiveness of operation of the present caps.

Another object of the invention is to provide a simple, practical and effective method of manufacturing stoppers embodying the invention.

In the accompanying drawings Fig. 1 is a side elevation of a bottle stopper embodying my present invention;

Fig. 2 is a bottom plan view of the same;

Fig. 3 is a plan view of a piece of material from which a plurality of stoppers are made, showing the manner in which this is done; and

Fig. 4 is an end elevation of the piece of material shown in Fig. 3.

Figure 5 is a top plan view of the cap with the tab 2 folded down upon the stopper.

Referring to the drawings I show in Fig. 1 a bottle stopper comprising a piece of material such as cardboard made into a body part 1 and a tab 2. The body member 1 is preferably circular so as to fit in the top of a milk bottle and the tab 2 is in the form of

a projection from the body member 1, preferably with sides tangential to the body part and meeting one another preferably at a right angle. This makes a convenient shape of tab to be taken hold of by the fingers to lift the stopper out of a bottle.

As shown in Fig. 2 the stopper may be constructed very effectively and inexpensively by stamping the same from a piece of suitable material 3, as for example, cardboard. In such case the body part 1 of each stopper will be stamped by a circular die or other device and the tab 2 will be formed by the corner of the piece of material which is not cut from the body part 1. In other words the material will be so stamped as to cut out the pieces marked 4-4-4, and also the central piece marked 5, leaving, however, the four corners 2-2 attached to the otherwise circular body members 1. Thus the stoppers may be very quickly made, requiring but a single stamping operation to make them in quantity, and furthermore material will not be wasted and consequently economy will be secured, because the entire width of the material is used for the stoppers and only intermediate portions of material are thrown away.

As shown in Fig. 1, the tab 2 is under-cut at the point 10 so as to provide a shoulder 11 which is arcuate and forms a continuation of the circumferential periphery of the cap. The tab 2 is further bent at the point 12, on a chord of the circle, from the shoulder 11, so as to leave the shoulder 11 unobstructed and to form tight contact with the walls of the rabbet in the usual milk bottle, thereby preventing leakage or the ingress of dust into the bottle.

As will be observed from Fig. 5, to bend the tab on a chord of the circle it is necessary that the bottle cap be split inwardly as indicated at 13.

It will be understood that changes and modifications may be made without departing from the spirit of the invention.

What I claim is:

1. A bottle cap comprising a flat disk body having an integral tab extending outwardly therefrom, said tab being foldable inwardly toward the body of the cap, the point of fold being within the confines of the body and substantially spaced from the edge thereof.

2. A bottle cap comprising a circular body

having an integral tab extending from the edge of said body, said tab being of less thickness than the circular body of the cap at the point of juncture with the body thereby forming a shoulder at the point of juncture between the body and the tab, said shoulder forming a continuation of the peripheral edge of the body.

3. A bottle cap comprising a circular body 10 having an integral tab extending from the edge of said body, said tab being of less thickness than the circular body of the cap at the point of juncture with the body thereby forming a shoulder at the point of juncture between the body and the tab, said shoulder forming a continuation of the peripheral edge of the body, said tab being adapted to be bent inwardly on a chord within the confines of said circular body portion.
- 15 4. A bottle cap comprising a flat circular body having an outwardly extending integral tab on its peripheral edge, said tab having its sides extending tangentially to the

periphery of said body and meeting at substantially right angles, an arcuate shoulder 25 formed by notching the under side of said cap at the juncture of said tab and said body, said shoulder forming a continuation of the peripheral edge of the cap, for the purposes set forth.

5. A bottle cap comprising a circular disc, the edge of said disc being split horizontally to produce an integral tab, said tab being foldable on a secant of the circular body.

6. A bottle cap comprising a flat circular body having an outwardly extending integral tab on its peripheral edge, an arcuate shoulder formed by notching the under side of the cap at the juncture of said tab and said body, said shoulder forming a continuation of the peripheral edge of the cap, for the purposes set forth.

In witness whereof, I hereunto subscribe my name this 13th day of April, A. D. 1921.

ADOLPH Y. S. ALBUM.
